AUTOMOBILE

Friedrich K. H. Nallinger, Stuttgart, and Karl Wilfert, Stuttgart-Degerloch, Germany, assignors to Daimler-Benz Aktiengesellschaft, Stuttgart-Unterturkheim, Germany

Filed Jan. 4, 1960, Ser. No. 58,904

Claims priority, application Germany July 4, 1959

Term of patent 7 years

(Cl. D14—3)

FIG. 1

FIG. 2

FIG. 3

FIG. 4

FIGURE 1 is a perspective view taken from the rear of an automobile showing our new design;

FIGURE 2 is a rear elevation of this invention;

FIGURE 3 is a side elevation according to this invention; and

FIGURE 4 is an enlarged perspective view of a tail light according to this invention.

The dominant features of our design reside in the portions shown in solid lines in the drawings.

Portions of the automobile are omitted in FIGURES 3 and 4 for convenience of illustration.

We claim:

The ornamental design for an automobile, substantially as shown and described.
